(57) **CLAIM**

The ornamental design for a grooming device, as shown and described.

DESCRIPTION

FIG. 1 is a top perspective view of a grooming device showing the claimed design;

FIG. 2 is a bottom perspective view thereof;

FIG. 3 is a front plan view thereof;

FIG. 4 is a rear plan view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines in the figures show portions of the grooming device that form no part of the claimed design.

1 Claim, 8 Drawing Sheets
